W. J. TURNBULL

MACHINE FOR USE IN CONJUNCTION WITH MOTOR IN PROPELLING A BOAT

Filed May 14, 1923

INVENTOR
WILLIAM J. TURNBULL.

BY

Feekes & Daugherty
ATTYS.

UNITED STATES PATENT OFFICE.

WILLIAM JAMES TURNBULL, OF MANVILLE, ALBERTA, CANADA.

MACHINE FOR USE IN CONJUNCTION WITH MOTOR IN PROPELLING A BOAT.

Application filed May 14, 1923. Serial No. 639,019.

To all whom it may concern:

Be it known that I, WILLIAM JAMES TURNBULL, of the village of Manville, in the Province of Alberta, Canada, having invented a new and useful Machine for Use in Conjunction with Motor in Propelling a Boat, do hereby declare that the following is a full, clear, and exact description of the same.

10 This invention relates to improvements in motor boats and particularly to improvements in means for attaching the motor to the boat, and the objects of the invention are to provide improved means of this character

15 preferably for motors of the direct drive type in which the housing or tube encloses the shaft and supports it from the base of the engine to the propeller.

Further objects are the provision of means 20 intermediately connected to the tube whereby the engine is adapted to be swung on its bearings, permitting the motor to be installed further forward in the boat than has been possible with the construction heretofore used.

Still further objects are the provision of means whereby the motor is secured to a solid engine bed and sits lower in the boat, this providing a steadier boat while permitting 30 the engine to tilt on its bearings, thus lowering and raising the propeller at will with the shaft, the propeller rising out of the water to the stern of the boat, thereby allowing accessibility to it, the propeller being also protected from injury when meeting 35 with any obstruction.

With the foregoing and other objects in view, the invention consists essentially in the novel arrangement and construction of 40 parts as described in the present specification and illustrated by the accompanying drawings that form part of the same.

Referring now to the drawings, in which like characters of reference indicate corresponding parts in each figure,

45 Figure 1 is a side elevation, showing the position of the propeller when the engine is tilted upwardly, with dotted lines showing the position of the device in relation to the stern-piece when the engine is tilted downwardly.

50 Figure 2 is a side elevation of the housing with means for swingingly mounting the engine and also adapted to receive the propeller shaft.

Figure 3 is a plan view of Figure 1.

Figure 4 is a longitudinal section.

Figure 5 is a detail plan view of the receiving member for the propeller shaft.

Figure 6 is a section through the receiving member.

Figure 7 is an end view of the stern.

Figure 8 is a section on line 8—8 of Figure 4.

Figure 9 is a section on line 9—9 of Figure 4.

Figure 10 is a front end view, with the receiving member and engine supporting bracket removed.

Figure 11 is a detail of the bracket for 70 swingingly supporting the engine and adapted to be attached to the main body.

In the drawings, 10 designates a housing adapted to fit the stern end of a boat and so formed that part of the rear end and bottom 75 are in open communication with the water. 11 is a bearing bracket connected to the forward end of the housing and having journalled therein a trunnion shaft 12 permanently connected to the engine 13 of the 80 usual standard construction and provided with a propeller shaft 14, in turn provided with a tubular covering 15 adapted to envelop the shaft and formed at its rear end with a web 16. The forward end of this 85 tube passes through a flexible packing gland 17, as shown in Figure 5, and designed to be fixedly secured on the end of the housing 10. 90

From the foregoing it will be noted that the engine is adapted to tilt on the bearings 18.

The flexible packing gland 17 is constructed of pliable waterproof material, preferably of tubular shape, and is provided with 95 a central aperture 19 and also an outside metal ring 20 having orifices therein whereby the gland is fixedly secured to the front end plate 21, as shown in Figure 10, of the housing, the tubular aperture in the gland 100 registering with the aperture 22 in the end plate, the inner end of said aperture 19 being provided with a metal sleeve 23 adapted to connect with the engine 13, thus allowing the shaft and housing to tilt with the engine and at the same time adapted to form 105 an effective protection against the water coming into the boat.

In Figure 1 is illustrated the position of the propeller when the engine tilts upwardly 110

and also, in dotted lines, the opposite position when the engine is tilted downwardly.

The housing is also provided with a projection 24 adapted to extend into the openings made for it in the stern-piece and keel, or, if desired, the housing can be made without this projecting flange.

To lock the propeller shaft a foldable lever 25 is provided, connected at one end to the propeller and extending upwardly and outwardly through the top of the housing 10.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. In a propelling device, the combination with a housing adapted to fit the stern end of a boat, said housing being formed so that part of the rear end and bottom are in open communication with the water, a bearing bracket connected to the forward end of the housing, a trunnion shaft journaled in said bracket and permanently attached to an engine, a propeller shaft connected to the engine, a tube enveloping the shaft, with a web formed on its rear end, the forward end of the tube being designed to pass through a flexible packing gland connected to the housing and secured to the engine, means

connected intermediate the tube to swing the engine in its bearings.

2. In a propelling device of the character described, the combination with a suitable housing adapted to communicate with an opening in the bottom of a boat, a bearing bracket connected to the forward end of the housing, an engine tiltably mounted in said bracket, a propeller shaft connected to the engine, a tube for said shaft and flexible means connecting the tube with the engine, comprising a flexible packing gland fixedly connected to the housing and adapted to receive therethrough said tube and rigid means carried by the flexible gland adapted to connect the gland to the engine whereby on the engine being tilted a hinging point is formed by the gland to tilt the propeller shaft.

3. In a device of the character described, the combination with a suitable housing and an engine tiltably mounted on the outside of the housing and having a propeller shaft extending through the housing, of tubular means on said shaft and flexible gland means on the housing adapted to engage with the tube means and provided with rigid means to connect with the engine whereby a hinging point is formed between the housing and the tiltably mounted engine to tilt the propeller shaft, and means for locking the propeller shaft when tilted.

WILLIAM JAMES TURNBULL.
